UNITED STATES PATENT OFFICE

ZADOK STREET, OF SALEM, OHIO.

IMPROVEMENT IN BRICK AND TILE MACHINES.

Specification forming part of Letters Patent No. 35,843; dated July 8, 1862.

To all whom it may concern:

Be it known that I, ZADOK STREET, of Salem, in the county of Columbiana and State of Ohio, have invented a new and useful Machine for Making Bricks and Tiles; and I do hereby declare the following to be a full and exact description of the same, reference being had to the accompanying drawings, making part of this specification, in which—

Figure 1 is a vertical section of the machine at x x , Fig. 2. Fig. 2 is a vertical section of the same at y y , Fig. 1. Fig. 3 is a perspective view of the pressing-machine, hereinafter described.

Similar letters of reference indicate corresponding parts in the several views.

The nature of the invention consists, first, in certain devices by which the clay to be pressed is separated from that in the mill and afterward pressed equally into the several molds; second, in an improved device for separating the surplus clay from that within the molds before withdrawing the latter.

To enable those skilled in the art to fully understand and use my invention, I will proceed to describe its construction and operation.

A represents the grinding-mill, having the customary toothed shaft, B, which is rotated by a sweep, C. a a are apertures in the lower part of the grinding-mill, communicating with pressing-machines constructed as follows:

D is a shell or box open at the top, serving to receive the clay as it comes from the mill.

E is a sliding gate employed to close the apertures a , and thus separate the clay which is to be pressed into the mold from that which remains in the mill. The said gate may be drawn down by means of a treadle, F, connected to it by means of links f and retracted by springs G.

H is the follower hinged by one edge to the gate E, near the lower edge of the latter.

h is a lever for forcing down the follower to press the clay into the molds, as hereinafter explained.

I is a movable mold provided with partitions i , which are formed of glass or analogous substance adapted to impart a smooth surface to the bricks. The bottom, ends, and sides of the molds are also lined with the same material.

J J J are bars secured across the box D immediately above and corresponding with the positions of the partitions i .

K is a wire cutter attached at each end to a bar, L, sliding on guides l l . This cutter is more clearly represented in Fig. 3.

The operation of the machine is as follows: The box D having become full of tempered clay from the mill A, the gate E is forced down by means of the treadle F, closing the communication with the mill. The hinged follower H is then drawn down by means of the lever h , the effect of which is to force the clay at once downward and outward, completely filling the molds to their extreme outer ends. The bars J have the effect of separating the clay at a distance above the molds, so that an equal quantity may be pressed into each, and equality in the manufacture thus insured. When the bricks in the molds are sufficiently pressed, the follower H and the gate E are allowed to rise. The wire or cutter K is then drawn forward, producing a smooth and even separation between the clay within the molds and that which is to be left within the box D. While the clay is passing from the mill into the box a carrier on one side of the machine pushes in an empty mold while another carrier on the other side withdraws the full one. By cutting the clay on a level with the top of the molds before withdrawing the latter bricks are produced as uniform and square in size and shape as those made by hand, the surface not being disturbed or put out of shape, as is commonly the case in the act of withdrawing the filled molds from brick-machines.

The lining of the molds with glass facilitates very much the removal of the bricks from the molds, and with but little labor imparts to the bricks as smooth a surface as is ordinarily produced under heavy pressure. The ease of withdrawing the bricks likewise permits the clay being worked in a much drier and stiffer condition than is ordinarily practicable, and hence the bricks better retain their form.

Tiles of any size and shape, dictated by their purpose and the character of the clay used, are made in the manner above explained by having the molds and other parts of form and dimensions adapted therefor.

Similar machines may be applied to the other

sides of the mill, but the one shown is deemed sufficient to illustrate the principles of the invention. A cut-off gate to close the apertures *a* may, if preferred, be made to slide up from below. Crank or cam power will be applied, if needful, to force down the hinged follower *H*.

I am aware that it is common to use metallic molds in brick-machines, and therefore do not desire to be understood as claiming this as my invention.

Having thus described my invention, what I claim therein as new, and desire to secure by Letters Patent, is—

1. The combination of the sliding gate *E*,

follower *H*, hinged thereto by its inner edge, and lever *h*, constructed, arranged, and operating in the manner described, to first separate the clay in the box *D* from that within the mill *A* and afterward press the former downward and outward into the molds *I*, all as specified.

2. The wire cut-off *K*, so arranged and operated, by means of bars *L* and guides *ll*, as to separate the surplus clay from that pressed into the molds, as hereinbefore described.

ZADOK STREET.
